CHUSETTS.

TRANSFORMER.

Application filed July 31, 1924. Serial No. 729,307.

Objects of this invention are to hold a plurality of wound bodies together in a simple manner, to provide a rigid and self-sustaining structure, and to provide a small 5 compact and inexpensive transformer in which the distributed capacity is reduced to a minimum.

In accordance with this invention a transformer may be provided in which the primary coil is placed between the secondary coils. The coils may be constructed similarly in the form of a web in which insulated wire is woven from the center outwardly, the turns of individual wires being spaced both 10 radially and axially from the turns of adjacent wires. Each wire preferably extends a substantial distance on one side of the coil before passing through to the other side, so that the exterior faces of the coils are substantially smooth and regular, and when finished the entire structure is relatively thin, rigid and self-sustaining. The secondary and primary coils are preferably held in predetermined relation by lattice work 15 which may consist of wires continued from one or both secondary coils criss-crossing the several coils, such for example as over the outer periphery of the transformer. The lattice work not only serves to hold the coils in predetermined relation to each other but, when the lattice work constitutes a part of the secondary coil or coils, it renders the magnetic linkage between the primary and 20 secondary more effective.

30 A preferred embodiment of the invention is illustrated in the accompanying drawings in which,—

Fig. 1 is a side view of a single coil;

Fig. 2 is a developed view of the coil showing the manner of winding;

Fig. 3 is a diagrammatic side view of the transformer;

Fig. 4 is a diagrammatic edge view of the transformer;

Fig. 5 is a developed view of the outer periphery of the transformer;

Fig. 6 is a developed view of the inner periphery of the transformer; and

Fig. 7 is an enlarged section on the line 7-7 of Fig. 1, the parts in back of the cut being omitted for the sake of clearness.

In the embodiment of the invention illustrated, a transformer A comprises annular coils *a*, *b*, and *c* of insulated wire, the inter-

mediate coil *b* preferably constituting the 55 primary coil and the coils *a* and *c* constituting the secondary coils. As hereinafter described the coils may be similarly constructed and are bound together at their peripheries to form a unitary structure which is 60 relatively thin, compact, rigid and self-sustaining.

One way of making each coil is by winding insulated wire in and out around a series of pins 1 which are placed radially at regular spaced intervals. As indicated in Fig. 2 each wire is wound over a plurality of pins (two in this instance) on one side, thence through to the other side of the coil and over the same number of pins and so on, 70 until the coil is of proper size, the number of pins being indivisible by the number of pins forming a single winding step so that the wire crosses through different spaces between pins in each turn. A web construction 75 is thereby produced in which the turns of the individual wires are spaced both axially and radially from the turns of adjacent wires and the exterior faces are substantially even and smooth.

80 A preferred way of making the transformer is to employ a form having three circular rows of radial pins spaced axially of the form. The central primary coil is first wound on the central row of pins as above described. One secondary coil is then wound on one of the end rows as above described and the wire extended over the primary coil to the other end row of pins, the second secondary coil being wound as a continuation of the first secondary coil. After the third coil is wound to the same diameter as the first two the criss-cross lattice work is wound as a continuation of the secondary wire. The lattice work is wound in a 85 manner similar to that of each coil except in that the wire crosses the entire width of the transformer back and forth between the two end rows of pins. Thus the primary comprises one wire having inner and outer ends 90 3 and 4; and the two secondaries and lattice work comprises a second wire having inner and outer ends 5 and 6, 7 indicating the cross-over from the outer periphery of the first secondary to the inner periphery of the 95 second secondary.

100 After the transformer is completely wound it is preferably dipped in a solution of cellu-

lose acetate, or other substance adapted to render the structure self-sustaining when dried, whereupon it may be removed from the form and the pins withdrawn.

5. I claim:

1. A transformer comprising a primary coil, a secondary coil on each side of said primary coil, and a wire wound back and forth across the outer peripheries of said coils for holding the coils in predetermined relation.

15. A transformer comprising a primary coil, a secondary coil on each side of said primary coil, means for spacing said coils from each other, and lattice work on the outer peripheries of said coils for holding them in predetermined relation.

20. A transformer comprising a primary coil, a secondary coil on each side of said primary coil, and wires criss-crossed on the outer peripheries of said coils for holding them in predetermined relation.

25. A transformer comprising a primary coil, a secondary coil on each side of said primary coil and a wire continued from one of the secondary coils wound back and forth across the outer peripheries of said coils for holding them in predetermined relation.

30. A transformer comprising a primary coil, a secondary coil on each side of the primary coil, and wire continuing from said secondary coils criss-crossed on the outer peripheries of said coils for holding them in predetermined relation.

35. 6. A transformer comprising a primary coil, a secondary coil on each side of said primary coil, means for spacing said coils from each other, and lattice work on the outer peripheries of said coils formed by continuing a wire from at least one of said coils for holding them in predetermined relation.

40. 7. A transformer comprising a primary coil, a secondary coil on each side of said primary coil, means for spacing said coils from each other, and lattice work on the outer peripheries of said coils comprising a continuation of the wires from said secondary coils for holding them in predetermined relation.

45. 8. A transformer comprising a primary coil, a secondary coil on each side of said primary coil, said coils constructed of insulated wire woven from the center outwardly, the turns being spaced both axially and radially, and a wire wound back and forth on the outer peripheries of the coils for holding them in predetermined relation.

50. 9. A transformer comprising a primary coil, a secondary coil on each side of said primary coil, said coils constructed of insulated wire woven from the center outwardly, the turns being spaced both axially

and radially, and wires continued from said secondary coils criss-crossed on the outer peripheries of said coils for holding them in predetermined relation.

55. 10. A transformer comprising a primary coil composed of concentric layers of insulated wire having a series of radial apertures, each wire passing more than one aperture before crossing to the opposite face, the total number of apertures being indivisible by the number of apertures forming a single winding step, secondary coils similarly constructed to said primary coil on opposite sides thereof, and insulated wires wound back and forth across the outer peripheries of said coils for holding them in predetermined relation.

60. 11. A transformer comprising a primary coil composed of concentric layers of insulated wire having a series of radial apertures, each wire passing more than one aperture before crossing to the other face, secondary coils on opposite sides of said primary coils, and wires wound back and forth across the outer peripheries of said coils for holding them in predetermined relation.

65. 12. A transformer comprising a primary coil composed of concentric layers of insulated wire having a series of radial apertures, each wire passing more than one aperture before crossing to the other face, secondary coils similarly constructed to said primary coil on opposite sides thereof, and lattice work on the outer peripheries of said coils composed of wires continued from the secondary coils.

70. 13. A transformer comprising a primary coil composed of concentric layers of insulated wire having a series of radial apertures, each wire passing more than one aperture before crossing to the other face, secondary coils similarly constructed to said primary coil on opposite sides thereof, and lattice work on the outer peripheries of said coils composed of wires continued from the secondary coils.

75. 14. An article as hereinbefore described comprising a plurality of relatively thin wound bodies, and lattice work on the outer edges of said bodies consisting of a continuation of the windings of at least one of said bodies for holding said bodies together.

80. 15. An article as hereinbefore described comprising a plurality of relatively thin wound bodies, means for spacing said bodies from each other, and lattice work consisting of a continuation of the windings of at least one of said bodies for holding them in predetermined relation.

85. Signed by me at Providence, R. I., this twenty-ninth day of July, 1924.

DWIGHT BRADFORD HILL.
